RECEPTACLE CLOSURE

William Kaufman, Mount Vernon, N. Y.

Application June 6, 1935, Serial No. 25,265

5 Claims. (Cl. 221—64)

The invention relates generally to receptacle closures and more specifically to a closure adapted to conveniently dispense the contents of tooth powder receptacles or the like.

5 The main object of the invention resides in the provision of a receptacle having an opening in the wall of the cover member thereof, whereby powder contents from the said receptacle are dispensable by the use of the same hand that grasps 10 the said receptacle.

A further object of the invention resides in the provision of a receptacle of the above type wherein the cover member is provided with a simple and durable mechanism adapted to successively deposit a small quantity of the powder contents on a brush, such as a tooth brush, during the revolution of a rotary element mounted on the cover member of the said receptacle.

An incidental object of the invention resides 20 in the provision of means for uniformly distributing powder on a tooth brush without loss or waste of powder during the depositing operation. In addition the invention affords other features, such as the simplicity and durability of construction, the serviceability and efficiency in use and 25 low cost of manufacture.

These objects and other incidental ends and 30 advantages of the invention will hereinafter appear in the progress of the disclosure and as pointed out in the appended claims.

Accompanying this specification are drawings 35 showing three preferred embodiments of the invention and wherein corresponding reference numerals designate corresponding parts throughout the several views.

From the drawings:

Figure 1 is a side elevation of the first preferred form of the invention.

40 Figure 2 is a front elevation of Figure 1.

Figure 3 is a plan view of Figure 1 partly broken away.

Figure 4 is a fragmentary sectional view of Figure 3 through the plane 4—4 thereof.

45 Figure 5 is a plan view of the second preferred form of the invention being partly in section and partly broken away.

Figure 6 is a sectional view of the second preferred form of the invention along the vertical plane of the axis showing the upper portion of the cover and receptacle.

50 Figure 7 is a fragmentary and sectional view of the left side of Figure 6 showing another construction of a baffle plate.

Figure 8 is a plan view of the inside of the in-

ner surface of the cover member of a receptacle which is circular in cross section.

Figure 9 is a diametrical sectional view of the upper portion of a receptacle which is circular in cross section and wherein the upper wall of a cover member is provided with an opening for the dispensing of powder contents.

In accordance with the invention and in accordance with the accompanying drawings, numeral 10 designates the continuous vertical wall 10 of a container such as a tooth powder container, while numeral 11 represents the bottom wall of the said container having a beaded periphery. In Figures 3 and 5, the receptacle is shown as being elliptical in cross section, while in Figure 8 15 the receptacle is shown as being circular in cross section. It is distinctly understood, however, that any other geometrical shape of a receptacle in cross section may be resorted to wherever desirable. The wall 10 at one side of the receptacle 20 is provided with a cut-away shoulder portion 10', the said shoulder portion 10' serving to allow free passage of powder contained in the receptacle through an orifice provided in the cover member of the said receptacle, the said cover member being designated by numeral 13. Below the upper limit of wall 10 of the receptacle and slightly below the lower limit of shoulder 10' is a bead 12 25 designed to serve as a limiting stop for the lower edge of the vertical wall of the cover member 13. Below the upper limit of wall 10 of the receptacle and slightly below the lower limit of shoulder 10' is a bead 12 30 designed to serve as a limiting stop for the lower edge of the vertical wall of the cover member 13. The cover member 13 is provided with a top wall 15 and an orifice 14 along the vertical wall of 35 the cover member and being intermediate the height thereof. As shown in Figure 1, orifice 14 is preferably located in the vertical plane of the longitudinal axis of the said cover member.

The top wall 15 of cover member 13 is provided with a rotary conveyor whereby powder from receptacle 10 is conveyed to and out of orifice 14 situated in the cover member.

40 The aforementioned rotary conveyor is mounted in the top wall of cover member 13 and comprises an upper disc 17 and a lower rotary conveyor 18. The upper disc 17 has a lipped and a preferably roughened outer edge 17', the said 45 edge projecting above the outer face of top wall 15 of the cover member and slightly beyond the rounded edge of the vertical wall of the cover member adjacent orifice 14. The rotary conveyor 18 comprises a circular vertical wall and a top 50 wall 18', the said circular wall having a series of radially and inwardly disposed recesses 19. Upper disc 17 and rotary conveyor 18 are keyed together above and below the top wall 15 of the cover member of the receptacle, by means of a 55

series of radially disposed spurs 20 adjacent the center of top wall 18'. The said spurs 20 result from notched out portions in the top wall 18' of the rotary conveyor and penetrate an orifice 16 in the top wall 15 of the cover member. Spurs 20 penetrate a series of radially disposed and aligned orifices in the center of upper disc 17, the said spurs being inwardly bent along the upper surface of disc 17, whereby the rotary conveyor 18 is made to rotate with the rotation of upper disc 17.

The first preferred form of the invention shown in Figures 1, 2, 3 and 4 is provided with a rotary conveyor 18 whose vertical wall is substantially tangent to the inner face of the vertical wall 13 of the cover member at orifice 14. At the same time the rotary conveyor 18 is confined within the vertical wall of the cover member of the receptacle. By inverting the receptacle containing powder such as tooth powder recesses 19 are filled therewith and by maintaining the receptacle in this position the contents of recesses 19 fall upon the bristles of a tooth brush when rotating disc 17 with the fingers of the same hand that grasps the receptacle.

Thus a dispenser is provided which eliminates waste and which is controllable with the same hand holding the tooth powder receptacle.

The second preferred form of invention is shown in Figures 5 to 8 inclusive. The second preferred form of the invention shows a receptacle having a continuous vertical wall 10a, a shoulder portion at one end thereof 10'', a bead 12' situated slightly below the lower limit of shoulder 10'', a cover member 13' and an orifice 14' in the vertical wall of the cover member substantially intermediate the height thereof. As shown in Figures 5 and 6 the vertical wall 13' of the cover member is provided with a baffle plate 13'' whereby the contents from the receptacle are prevented from flowing into the cover member and out of the orifice 14' when the receptacle is inverted for dispensing. The said baffle plate 13'' as shown in Figure 6 projects inwardly from the inner surface of the vertical wall 13' of the cover member while in Figure 7 a corresponding baffle plate 12'' is shown as being an integral and inward projection of the vertical wall 10a of the receptacle. 15' is the top wall of the cover member and is provided with an orifice 16' at the center of upper disc 17'' and rotary conveyor 18''. The said orifice 16' in top wall 15' is plugged by means of a central depression of the disc 17'', the said disc 17'' being provided with a lipped and roughened periphery 17'''. The rotary conveyor 18'' is provided with a series of teeth 19' constituting the vertical wall thereof. Spurs 20' projecting upwardly from the top wall 18''' of the conveyor penetrate the orifice 16' and the inner radially disposed orifices in the disc 17''. The said spurs are inwardly bent along the upper face of the said disc 17''' thereby serving as the keying means between disc 17'' and rotary conveyor 18''.

Figure 8 shows a similar construction as presented in Figures 5, 6 and 7, except that the receptacle and cover member are circular in cross section, numeral 21 designating the vertical wall of the cover member and numeral 22 designating the orifice therein.

Figure 9, showing the third preferred form of the invention wherein the opening in the cover member is provided in the upper wall thereof, shows the vertical wall of the container designated by numeral 23, the top wall of the vertical container designated by numeral 24 and orifice 25 situated in the top wall 24 proximate to the

outer edge thereof. The upper wall 24 of the receptacle is provided with a circular orifice 26. Upper wall 24 of the receptacle is provided with a rotary conveyor whereby powder from receptacle 23 is conveyed to and out of orifice 25, the said rotary conveyor being comprised of an upper disc 32 and a lower rotary conveyor 27. The upper disc 32 has a lipped and preferably roughened edge 34, the said edge projecting above the upper surface of disc 32. The rotary conveyor as designated by numeral 27 comprises a circular vertical wall and a top wall, said top wall also being designated by numeral 27, the said circular wall having a series of radially and inwardly disposed recesses 29. Upper disc 32 and lower conveyor 27 are keyed together above and below the upper wall 24 of the receptacle by means of a series of radially disposed spurs 30 adjacent the central orifice 26 of the upper wall 24. The said spurs 30 result from notched out portions in the upper or top wall of the rotary conveyor, penetrating orifice 26 in the upper wall 24 of the receptacle. Spurs 30 penetrate a series of radially disposed and aligned orifices in the center of upper disc 32, the said spurs being inwardly bent along the upper surface of disc 32, whereby the rotary conveyor 27 is made to rotate with the rotation of upper disc 32.

The upper disc 32 is provided with a series of radially disposed orifices 33 which said orifices 33 register with orifice 25 of the upper wall 24 of the receptacle during rotation of the said disc. Upper disc 32 is provided with a funnel member 35 which serves as a spout from which the powder contents issuing from the receptacle through the registration of any one of orifices 33 with orifice 25 are deposited on the brush. The said spout 35 is mounted in the usual manner to upper disc 32, but as shown is brazed to the inner wall of lip 34. The vertical wall 23 is provided with a baffle plate 31 whereby the contents from the receptacle are prevented from flowing into the funnel member 35 when the receptacle is inverted for dispensing purposes. As shown, baffle plate 31 is an integral and inward projection of the vertical wall 23 of the receptacle.

From the foregoing description of the three preferred forms of the invention it can readily be seen that the invention is adaptable for use on any receptacle regardless of shape, even in those receptacles wherein the dispensing mechanism resides in the reduced neck portion. It is to be understood that the shape of the receptacle, of the disc and rotary conveyor, and the nature of the recesses in the rotary conveyor can be changed to suit the taste of the manufacturer without departing from the spirit of the invention and without departing from the scope of the appended claims.

It is also to be distinctly understood that minor changes and variations in the integration of the several parts of the invention and the materials used and in the location of parts, may all be resorted to without departing from the spirit of the invention and without departing from the scope of the appended claims.

I claim:

1. A receptacle closure comprising a receptacle, a cover member having a top and side walls, the said side wall having an orifice therein, a rotary conveyor mounted on the inner side of the top wall of the cover member and having a plurality of spaced indentations along the sides thereof, a disc member mounted on the outer side of the top wall of the cover member and being keyed to the

rotary conveyor whereby upon rotation of the said disc member the spaced indentations register with the said orifice.

2. A receptacle closure comprising a receptacle,
- 5 a cover member therefor having top and side walls, the said side wall having an orifice therein, a rotary conveyor mounted on the underside of the top wall of the cover member and having a plurality of spaced indentations along the sides
- 10 thereof, the said indentations registering with the said orifice during rotation of the rotary conveyor, means on the cover member to rotate the said rotary conveyor.

15 3. A receptacle closure comprising a receptacle, a cover member therefor having top and side walls, the said side wall having an orifice therein, a rotary conveyor mounted on the underside of the top wall of the cover member and having a plurality of spaced indentations along the sides thereof, the said indentations registering with the said orifice during rotation of the rotary conveyor, a plate member to cover access of the contents of the said receptacle into the said indentations adjacent the said orifice, means on the cover member to rotate the said rotary conveyor.

4. A receptacle closure comprising a receptacle, a cover member therefor having top and side walls, the said side wall having an orifice therein, a ro-

tary conveyor mounted on the underside of the top wall of the cover member and having a plurality of spaced indentations along the sides thereof, the said indentations registering with the said orifice during rotation of the rotary conveyor, means on the cover member to rotate the said rotary conveyor, and a segmental plate member serving as a closure from beneath of those indentations adjacent the said orifice.

5. A receptacle closure comprising a receptacle, 10
an upper cover member therefor, the said cover
member having an orifice therein for the flow of
the contents from within the said receptacle, a
rotary conveyor mounted on the inner side of the
said upper cover member and having a plurality 15
of spaced indentations along the sides thereof, a
plate member to cover access of the contents of
the said receptacle into the said indentations ad-
jacent the said orifice, a disc member mounted on
the upper side of the upper cover member and 20
being keyed to the rotary conveyor, means of com-
munication from the rotary conveyor to a point
external to receptacle whereby upon inverting the
receptacle and upon rotation of the said disc
member the contents of the said receptacle are 25
discharged.

WILLIAM KAUFMAN
